FURNACE WALL STRUCTURE

Filed Nov. 2, 1931

Inventor:
Frank B. Bigelow
and Walter M. Fullen

UNITED STATES PATENT OFFICE

FRANK B. BIGELOW, OF DETROIT, MICHIGAN, ASSIGNOR TO BIGELOW-LIPTAK CORPORATION, OF DETROIT, MICHIGAN, A CORPORATION OF MICHIGAN

FURNACE-WALL STRUCTURE

Application filed November 2, 1931. Serial No. 572,525.

My invention concerns furnace-walls and similar or analogous constructions and relates more particularly to improvements in the metal framework which supports the bricks or refractories and to the manner of mounting the latter in position on such supporting structure.

In a sense, the present invention may be considered as an improvement on that of Patent 1,670,490, granted to Jack E. Bigelow on a furnace wall construction, May 22, 1928.

One aim of the current invention is to provide a metal framework employing rolled beams or bars because of the smoothness of such members as distinguished from or contrasted with castings, and because such rolled elements, when used as horizontal supporting means for the bricks, can be employed 20 to span wider spaces between the upright columns than can similar cast-metal parts.

As a result, the columns can be spaced farther apart than has heretofore been customary, and the framework as a whole may be 25 lighter in weight without sacrifice in the required strength and rigidity.

A further purpose of the invention is to supply a furnace-wall in which the associated framework and the bricks or tiles which it 30 carries form a substantially air-tight construction, avoiding the infiltration or leakage therethrough of an excess or undesired amount of air from the outside.

To enable those skilled in this art to understand the invention fully and to provide a basis for the comprehension of its accruing benefits and advantages, in the accompanying drawing, forming a part of this specification, a present, preferred embodiment of 40 the invention has been illustrated in detail.

In this drawing:—

Figure 1 is a fragmentary, vertical section through the improved furnace wall; and

Figure 2 is a fragmentary face view of the 45 wall with some of the bricks in position; this view being on a smaller scale than that of Figure 1.

For simplicity, like reference numerals 50 have been employed in both figures to designate the same parts.

Referring to this drawing, it will be noted that the novel and improved furnace-wall comprises an upright metal framework composed of the required number of suitably-spaced, vertical columns 10, 10, which may be preferably the ordinary, rolled I-beams of commerce.

By means of bolts 11, 11, which may have relatively-small heads 12 disposed inwardly of the wall, with their nuts 13 arranged outwardly of the wall, the needed number of vertically-spaced, rolled-metal Z-bars 14, 14 are fastened against the inner surfaces of the columns, with their outer, upstanding flanges 15 bearing against the columns, their 65 webs 16 projecting inwardly of the furnace, and their inner, depending flanges 17 being spaced away from the columns, as will be readily understood and as is clearly shown in the drawing.

The securing bolts 11 are accommodated or received in registering holes in the flanges 15 of the Z-bars and in the contacting flanges of the upright columns.

The webs and flanges of these Z-bars are 75 continuous and are without recesses or apertures, except those hereinabove referred to, and, owing to the fact that such bars are the usual rolled members of trade and commerce, the columns may be spaced apart a 80 greater distance than has heretofore been usual when cast-metal elements have been used in place of the Z-bars.

Stated somewhat differently, the Z-bars, being common structural steel, will span 85 greater distances than castings of equivalent cross-sectional area.

A limiting factor in such castings is the length in which they can be cast or poured and still retain the required uniformity of shape without warping.

Such restricting characteristic, however, is not involved in the employment of the rolled Z-bars.

Due to the use of such rolled bars, as contrasted with the employment of castings heretofore used in the same relation, a substantial saving in the production of the framework is possible, and other advantages 100

accrue, as will be perceived from what follows.

Each such horizontal Z-bar 14 demountably carries a row of main bricks or refractories 18 which rest directly on the top face of the web 16 of the bar, some of the bricks at least having recesses or grooves 19 in their back or outer faces to receive the bolt-heads 12 and to permit the outer surfaces of the bricks to be in contact with the front face of the upstanding flange 15 at 20.

Each brick has a bottom extension 21, the back wall of which bears against or contacts with the front face of flange 17 at 22, and it also has a top projection 23 accommodated beneath the web of the Z-bar 14 next above with its inner face in bearing contact at 24 with the back surface of the flange 17 of such upper bar.

As shown, there is sufficient space between the top surface of the extension 23 and the under face of the web of the Z-bar 14 directly above it, and there is an adequate gap between the top face 25 of the main body 25 of the brick and the bottom edge of the adjacent flange 17 to allow the brick to be raised enough to permit its rocking or turning action to let the brick be inserted in the position shown or to remove it from the frame-work.

Rows of filler-bricks 26 are interposed between the separated rows of main bricks 18, resting on the top surfaces 25 of the latter in front of the adjoining flanges 17.

Obviously, such filler-bricks may be readily inserted in position or removed and, when they are in place, they lock the main bricks in location and prevent their removal, but when they are taken out, the main bricks may be demounted and replaced in the manner stated above.

A layer of cement, clay, or the like 27 may be employed between the tops of the filler-bricks 26 and the main bricks 18 just above.

The two sets or groups of bricks may be arranged in straight, vertical rows, as shown in Figure 2, or the bricks 26 may be employed in staggered or offset relation to the other refractories.

Inasmuch as continuous or unbroken rolled-steel Z-bars are employed in this construction for supporting or carrying the bricks, and since such bars have smooth surfaces unmarred by burrs or other imperfections likely to occur in castings, the bricks or refractory shapes, which have flat, plane surfaces, produced as by dry pressing, are brought into firm and intimate contact with the bars in such manner as to make the wall substantially free from any objectionable passage or leakage of air therethrough.

In this connection, it should be perceived that the suspension pressure of the bricks or tiles 18 assures proper and efficient seals between the Z-bars and the refractories at the

points 24 and 22 and also between the bottoms of the bricks and the tops of the webs of the bars, such seals or joints being further fortified by the contact of the bricks with the front faces of the flanges 15, whereby the wall is tight against air leakage for all practical purposes.

Thus the double advantage is gained of being able to use a lighter framework and at the same time obtain a better sealed wall than has heretofore been available in this general style or type of structure.

Those acquainted with this art will readily understand that the invention is not limited to the precise and exact details of construction shown and described, and that various modifications may be resorted to without deviation from the principles of the invention as defined by the appended claims, and without foregoing any of the substantial advantages accruing from the employment of the invention.

I claim:

1. In a furnace-wall structure or the like, the combination of upright columns, horizontal rolled metal Z-bars secured to said columns in vertically spaced relation with their upstanding flanges against said columns and their depending flanges spaced inwardly away from said columns, a row of bricks resting on the horizontal web of each of said Z-bars, each such brick having a top projection accommodated back of and bearing against the inner flange of the next Z-bar above, and rows, of filler-bricks between and resting on said rows of bricks and positioned in front of the inner flanges of said Z-bars.

2. In a furnace-wall structure or the like, the combination of upright columns, horizontal rolled metal Z-bars secured to said columns in vertically spaced relation with their upstanding flanges against said columns and with their depending flanges spaced inwardly away from said columns, a row of bricks resting on the horizontal web of each of said Z-bars, each of said bricks having a depending portion in front of and bearing against the front face of the inner depending flange of the Z-bar, each of such bricks also having a top projection accommodated back of and bearing against the inner flange of the next Z-bar above, and rows of filler-bricks between and resting on said rows of bricks and positioned in front of the inner flanges of said Z-bars.

3. In a furnace-wall structure or the like, the combination of upright columns, horizontal rolled metal Z-bars secured to said columns in vertically spaced relation with their upstanding flanges against said columns and with their depending flanges spaced inwardly away from said columns, a row of bricks resting on the horizontal web of each of said Z-bars, each of said bricks bearing against the outer upstanding flange of the bar and

having a depending portion in front of and bearing against the front face of the inner depending flange of the Z-bar, each such brick also having a top projection accommodated back of and bearing against the inner flange of the next Z-bar above, and rows of filler-bricks between and resting on said rows of bricks and positioned in front of the inner flanges of said Z-bars.

10 4. In a furnace-wall structure or the like, the combination of upright columns, horizontal metal members secured to said columns in vertically-spaced relation, each of said members having a depending flange spaced 15 inwardly of the furnace away from said columns, a row of bricks resting on each of said members, each such brick having a top projection accommodated back of and bearing against such flange of the next member above 20 and having a downward projection in front of and bearing against the flange of the member on which the brick rests, and rows of filler-bricks between and resting on said rows of bricks in front of said member flanges.

25 In witness whereof I have hereunto set my hand and seal.

FRANK B. BIGELOW.
